CLAIM

The ornamental design for a bottle opener, as shown and described.

DESCRIPTION

FIG. 1 is a front, right and top perspective view of a bottle opener, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of portion of FIG. 2 thereof.

The dash-dash broken lines shown in FIGS. 1-9 illustrate portions of the bottle opener that form no part of the claimed design; The dot-dash broken lines shown in FIGS. 2 and 9 are for purposes of annotating the enlarged view only and form no part thereof.

1 Claim, 9 Drawing Sheets(56)
